UNITED STATES PATENT OFFICE.

GEORGE ABRAM PARLEE, OF TACHE, CANADA.

RAILWAY-SIGNAL.

SPECIFICATION forming part of Letters Patent No. 659,097, dated October 2, 1900.

Application filed October 4, 1899. Renewed August 9, 1900. Serial No. 26,449. (No model.)

To all whom it may concern:

Be it known that I, GEORGE ABRAM PARLEE, station agent, of Tache, in the Province of Ontario, in the Dominion of Canada, have 5 invented certain new and useful Improvements in Railway-Signals; and I do hereby declare that the following is a full, clear, and exact description of the same.

My invention relates to railway-signals, and 10 particularly signal targets and lamps outside of way-stations. Its object is to provide a simple, strong, and accurate apparatus by means of which the target and the lamp are operated from within the station.

15 The invention consists in the form of apparatus employed and the combination of the parts, as shown in the annexed drawings, in which—

Figure 1 is a side view on a large scale. 20 Fig. 2 is a plan view of the table F and lever D. Fig. 3 is a plan view of the casting D.

A is a beam extending from the wall of the station and firmly secured to the brace A'. At the outer end of this beam A a casting B 25 is fitted, having its top portion circular and forming, with the end of the beam, the bearing of the spindle S. Over B fits the cap C, which is provided with a raceway for balls or rollers which run in a groove on the top 30 of the casting B. The lamp L fits on the top of the cap C. The target T is attached to the spindle S. A set-screw S' secures the spindle S to the cap C. A hand-lever D, situated in the station, operates the spindle R. Suitable 35 means are provided for operating the spindle S by the turning of the spindle R, the form shown in the drawings being two pulleys P' and P² and an endless chain or belt P, fastened to each pulley by screws P³ and P⁴, respectively. The handle D' of the lever D is 40 provided with a spring-catch D², which grips the table F and insures the proper amount of turn to the signal-spindle S.

Having now described my invention, what 45 I claim, and desire to secure by Letters Patent, is—

1. In a railway-signal, a lamp provided with a cap, C, and a spindle, S, depending from the same in combination with a socketed bearing- 50 plate for receiving the spindle, S, a bracket supporting the bearing-plate and antifriction-rollers arranged between the cap, C, and the bearing-plate, substantially as set forth.

2. In a railway-signal, a lamp provided with a cap, C, having a depending circular flange, 55 and a depending stem, S, in combination with a bracket, and a circular socketed bearing-plate, B, arranged thereon and provided with a circular groove and a series of antifriction-balls arranged in said groove, substantially 60 as set forth.

3. In a railway-signal, a lamp provided with a lower circular cap, as C, having a depending circular flange, and a stem, as S, depending therefrom, and a target, as T, attached to 65 said stem in combination with a bracket, a circular socketed bearing-plate for receiving the stem, S, supported by the bracket and provided with a circular groove, and a series of antifriction-balls arranged in the groove between the bearing-plate and the cap, C, substantially 70 as set forth.

4. In a railway-signal, a lamp provided with a lower circular cap, C, and a stem, as S, depending therefrom in combination with a 75 bracket provided with a socketed bearing-plate, B, for receiving the stem, S, a turning spindle arranged at a distance from the lamp-spindle, pulleys, P', P², secured one to the lamp-spindle and one to the turning spindle 80 and an endless belt or chain passing over the two pulleys and fastened to each pulley by fastening means, P³, P⁴, all substantially as shown.

5. In a railway-signal, a lamp provided with 85 a lower cap, C, having a circular depending flange and a depending stem, as S, provided at its lower end with a target, as T, in combination with a bracket, and a circular bearing-plate as B, mounted on said bracket and 90 provided with a circular groove, antifriction-balls arranged in said groove, a turning spindle parallel to the lamp-spindle, pulleys, P', P², mounted one on each spindle, a chain or belt passing over the pulleys and fastened to 95 each pulley by a screw, as P³, P⁴, all substantially as set forth.

I have hereunto set my hand, in the presence of the two undersigned witnesses, at Wabigoon, in the district of Rainy River and 100 Province of Ontario, Canada, this 20th day of March, 1899.

GEORGE ABRAM PARLEE.
